IMPULSE MEANS FOR ROTATING AMMUNITION PROJECTILES AT LOW SPEEDS

Robert M. Ramey, Havertown, Pa., assignor to the United States of America as represented by the Secretary of the Army

Application February 28, 1952, Serial No. 274,046

4 Claims. (Cl. 102—51)

(Granted under Title 35, U. S. Code (1952), sec. 266)

The invention described herein may be manufactured and used by or for the Government for governmental purposes without the payment of any royalty thereon.

Recent developments in the military weapon and ammunition art have led to the use of what has been termed the "shaped charge." This type of projectile, among others, requires a very minimum amount of spin while in flight, as too much spin has been known to spoil its armor-piercing or other such desired characteristics. On the other hand, some small amount of spin is necessary in order to offset the normal lack of symmetry in the manufactured parts. In the case of the gun and ammunition herein illustrated (Fig. 1), a recoilless firing device similar to that shown by Kroeger-Musser U. S. Patents 2,466,714 and 2,472,111 but employing a more recent type of projectile which is fin-stabilized, it has been determined that a suitable compromise between these two requirements is on the order of 10-20 revolutions per second.

Broadly stated, therefore, it is the principal object of my invention to provide a means for imparting a controlled, low rotative speed to projectiles fired from a gun rifled for normal spin stabilization of the projectile.

Another object is to accomplish such means in a fast, economical manner with a minimum amount of alteration being required for the ammunition and none for the gun.

These and other related objects are accomplished by my invention as will be seen by reference to the following specification and the annexed drawings, wherein:

Fig. 1 shows portions of a barrel and breech, in longitudinal section, of a rifled recoilless gun, together with a plan view of an ammunition round whose projectile's outer wall is knurled to effect a low speed spin in accordance with my invention;

Fig. 2 depicts an enlarged portion of the knurling on the projectile and the opposed barrel rifling as seen from line 2—2 of Fig. 1;

Fig. 3 is a much enlarged illustration of the knurled projectile portion (as shown in Fig. 1), on which has been super-imposed the bands of the rifled gun barrel just as if the view was through the gun's near wall which has been removed; and

Fig. 4 is a view of the knurled projectile portion similar to that shown in Fig. 1 except that the knurling is on the forward portion of the bourrelet proper, rather than just ahead of the bourrelet as in the Fig. 1 representation.

Prior art means for spin-inducing projectiles generally have relied upon mechanical engagement between the bore of the gun tube and the projectile. This was generally accomplished by helically rifling the gun barrel (as at 9—10 in Fig. 1), and providing around the projectile a rotating band which was relatively soft and cut its teeth and grooves in traversing the rifled barrel or else was preengraved to mesh with the riflings. Such spin-inducing means, however, invariably rotated the

2

projectile at a far faster speed than the 10-20 R. P. S. limitation above mentioned. By comparison, from the drawings and the following description it will be noted that I have accomplished the aforementioned objects by uniquely knurling, milling, shaping or broaching grooves in the projectile's outer wall to allow propellant gas to stream thereinto and thus cause the projectile to spin for reasons which will be explained below. In this way, the tremendous energy of the propellant gases used to place the projectile in flight is likewise employed to do the job of spinning the projectile. Since some of the gases which evolve when the ammunition is fired will course through the length of the barrel between the projectile and the barrel wall and in the grooves of the riflings in the gun tubes, those gases are allowed to expand into the grooves on the projectile wall and exert rotative force against the teeth-like walls thereof.

For a better understanding of my invention the various components shown in the drawings will now be identified and their functions briefly described. The conventional gun shown is of a recoilless type (although obviously my invention need not be limited to use with such guns), of which a barrel 8, having rifling lands 9 and grooves 10, and a rearwardly expanding chamber 11 are illustrated. The ammunition round consists of a projectile 12 having a rearward extension 13 which nests inside a cartridge case 14. Extension 13 optionally bears a number of flight-stabilizing fins 15 (only one is shown). Propellant powder 16 surrounds the projectile extension. Although the illustrated ammunition is of a special form to which my invention need not be limited, it has been selected as an example primarily because it represents a type which happens to be most effective when its projectile is given a minimum spin, and therefore my improvements are ideally suited thereto.

The projectile is provided with a bourrelet 20 which is the largest diameter portion of the projectile and thus, in well-known manner, serves as the "riding" surface which contacts lands 9 in moving forwardly through the barrel. In addition thereto, the bourrelet normally serves as a barrier to prevent the forward escape of gases except for those gases which escape therest through the rifling grooves of the barrel. On the forward portion or end of the bourrelet (as in Fig. 4), or on a lesser diametered region just forward of the rearward or uniform diametered portion of the bourrelet (as shown in Fig. 1) torque-inducing means comprising a plurality of teeth 22 and slots 23 are cut by any suitable means such as a knurling, gear hobbing, gear shaping, or broaching machine. The angle θ (see Fig. 3) between these teeth and the axial center-line of the projectile may be varied, depending upon the amount of projectile spin desired, the weight of the projectile to be spun, the force to be supplied by a particular propellant powder, the ballistic relationship of the projectile to the gun, etc. This angle may be determined quite readily either by calculation or empirically, as desired. Thus, the torque-inducing teeth or slots are each disposed along a line which forms an acute angle with or within an imaginary plane which is inclined with respect to the axial center-line of the projectile but which is inclined in an opposite sense as compared with the inclination of the imaginary planes including the gun's rifling lands with respect to the gun's axial center-line.

The operation of my invention should, by now, be apparent. The forwardly moving gases evolved upon ignition of propellant powder 16 will be caused by the gun's lands 9 to flow (as indicated by arrow 26 in Fig. 3) through grooves 10 along a line which forms the angle α with the projectile's axial center-line. When the

thus directionalized gases strike teeth 22 on the projectile wall they will be redirected thereby and move in a direction following slots 23 (as indicated by arrow 27 in Fig. 3). Although this deflection may not be imparted to all the gases immediately upon contacting teeth 22, by the time the gas passes over the toothed portion 22-23 of the projectile an adequate portion thereof will have had its direction and momentum changed.

This result, which can best be explained by reference to Fig. 2, is obtained by the propellant gases flowing along rifling grooves 10 over bourrelet 20, which has been supplied (dotted lines) in Fig. 2, and the toothed portion 22-23 of the projectile. Before the gases reach the toothed portion, in passing over the bourrelet they occupy only the space in the rifling grooves indicated by A; then they are led into the space represented as B. This increase in volume of passage caused by grooves 23 allows the gas to expand and increase its velocity. The direction of the grooves on the projectile is such that the direction of flow of part of the gas is changed by an angle equal to $\alpha + \theta$ (from Fig. 3), and continues to flow in this new direction.

The principle of the conservation of momentum requires that when a mass has its direction changed there is a resultant force. The changing of direction of that part of the propellant gas that flows into grooves 23 on the projectile surface causes a resultant force to strike teeth 22 which act like so many "turbine blades" and produce a torque-inducing effect thereby causing the projectile to spin. The angular rotation of the projectile will be in a clockwise direction as viewed from Fig. 2. Rotation in the opposite direction can, of course, be accomplished by slanting teeth 22 and grooves 23 in the opposite direction to that shown.

As will be evident, my invention can be adapted to many types of projectiles for use in various types of guns with very little and inexpensive alteration to ammunition rounds being required, and no change at all needed in the guns. The milling, knurling or other cutting of the teeth and slots in the projectile wall can be done very readily and inexpensively and, because the depth of slots or height of the teeth need be so relatively small, the projectiles in most cases will need no redesigning to provide adequate wall thicknesses therefor. Since the propulsion force is adequately supplied by gases that normally leak past the bourrelet, no additional powder will be required. Ballistically, the addition of my improvement has been found to cause no change in the ammunition's performance characteristics other than to give the projectile spins on the order of 10 to 20 R. P. S., as required.

It will therefore be noted that by my invention an effective means has been provided for imparting a controlled, low rotative speed to projectiles fired from a rifled gun, and this means can be accomplished in a fast, economical manner with a minimum amount of alteration being required for otherwise conventional ammunition, and none for the gun. Thus, one and the same rifled weapon is capable of firing projectiles rotated slowly by my herein described novel means, or rotated at much higher speeds by such prior art devices as mechanical engagement of rotating bands with gun barrel riflings, etc. This, of course, makes it possible for a gunner to put his weapon to dual usage—an invaluable asset in the field—without requiring different guns or special modifications thereof to fire projectiles at differing rotative speeds.

My invention will likewise be recognized as extensive in its adaptation and is not to be restricted to the specific form here shown and described by way of illustration.

I claim:

1. In an ammunition projectile to be fired from a rifled gun barrel, means for rotating the projectile at low speeds so as to offset the normal lack of symmetry of

its components, comprising, a bourrelet which is circumferentially located on the projectile between its forward and rearward extremities and whose external diameter forms a cylindrical surface of substantially uniform diameter, said bourrelet surface including a forward portion and a rearward portion, each said portion being adapted to slidably fit with the internal diameter of the gun barrel's rifling lands, said forward portion being grooved to provide torque-inducing vanes each of which is disposed within an imaginary plane which is similarly inclined with respect to the axial center-line of the projectile but which is inclined in an opposite sense as compared with the inclination of the imaginary planes including the gun's rifling lands with respect to the gun's axial center-line and within which the projectile is to be used, whereby some of the gases used to propel the projectile from the gun barrel will flow along the barrel's rifling grooves and over the projectile's bourrelet to impinge against the torque-inducing vanes so as to minimize normal rotation of the projectile otherwise imparted thereto by the rifled gun barrel.

2. In an ammunition projectile to be fired from a rifled gun barrel, means for imparting low-speed spin to the projectile so as to offset the normal lack of symmetry of its components, comprising a bourrelet which is circumferentially located on the projectile and whose external diameter form a cylindrical surface of substantially uniform diameter, said bourrelet surface including a forward portion and an adjoining rearward portion, each said portion being adapted to slidably fit with the internal diameter of the gun barrel's rifling lands, said forward portion having a plurality of slots in the surface thereof to provide ribs each of which is disposed within an imaginary plane which is similarly inclined with respect to the axial center-line of the projectile, the inclination thereof being disposed in an opposite sense as compared with the inclination of the imaginary planes including the gun's rifling lands with respect to the gun's axial center-line, whereby the gases used to propel the projectile from the gun barrel will flow along the barrel's rifling grooves and over said rearward portion of the projectile's bourrelet and out through said slots so as to minimize normal rotation of the projectile otherwise imparted thereto by the rifled gun barrel.

3. A device for imparting low-speed of rotation to a projectile to be fired from a rifled gun barrel, comprising a forward portion and an adjoining rearward portion located on the cylindrical outer surface of the projectile, each said portion being adapted to slidably engage the internal diameter of the gun barrel's rifling lands, said forward portion being grooved to provide a plurality of radially extending, torque-inducing teeth disposed on a line which forms an acute angle and inclined with respect to the axial center-line of the projectile, the inclination thereof being disposed in an opposite sense to the inclination of the gun's rifling lands with respect to the gun's axial center-line, said rearward portion comprising barrier means adapted for close engagement with the gun's rifling lands to prevent the gases used to propel the projectile from flowing therewith except substantially those gases travelling through the barrel's rifling grooves whereby such gases as do flow therewith will expand against said torque-inducing teeth to provide an impulse for minimizing normal rotation of the projectile otherwise imparted thereto by the rifled gun barrel.

4. In an ammunition round for use with a rifled gun barrel, a projectile having a maximum diameter portion thereof comprising barrier means dimensioned for slidably fitting the bore of the rifled gun barrel for substantially preventing the forward escape of gases used to propel the projectile from flowing therewith except those gases travelling through the barrel's rifling grooves, the forwardly disposed portion of said barrier means comprising a plurality of turbine-like blades circumferential-

ly disposed in spaced apart relation each on a line which forms an acute angle with a line parallel to the projectile's axial center-line, said blades being disposed inclined in an opposite sense to the inclination of the gun's rifling lands with respect to the gun's axial center-line, whereby expanding gases travelling along the gun's rifling grooves will be further expanded upon reaching the spaces between said blades and provide a torque-inducing impulse for minimizing normal rotation of the projectile otherwise imparted thereto by the gun barrel 10 rifling.
